Primary Examiner — Mitchell I. Siegel

(57) CLAIM

The ornamental design for a golf club head, as shown and described.

DESCRIPTION

FIG. 1 is a top perspective view of a golf club head; FIG. 2 is a bottom perspective view of the golf club head of FIG. 1;

FIG. 10 is a bottom perspective view of the golf club head of FIG. 9;

FIG. 16 is a toe side view of the golf club head of FIG. 9. The broken line showing is included for the purpose of illustrating unclaimed subject matter and forms no part of the claimed design.

1 Claim, 12 Drawing Sheets
